PUSH UP DELIVERY BARN GUTTER CLEANER

Harry O. Petraske, Fort Atkinson, Wis., assignor, by
mesne assignments, to Rockwood & Co., Chicago, Ill.,
a corporation of Delaware

Filed June 24, 1953, Ser. No. 363,788

12 Claims. (Cl. 198—224)

The present invention relates to a reciprocating barn gutter cleaner with an elevated delivery end wherein the operating parts are unitary and having a single power operating device.

An object of the present invention is to combine the gutter cleaner and elevator mechanism into a single unit so as to considerably reduce the initial cost and upkeep of the device.

The present invention is an improvement over my issued patents, No. 2,467,988, issued April 19, 1949, and No. 2,593,340, issued April 15, 1952, wherein separate means must be provided for delivering the litter from the barn into a manure spreader or wheeled conveyor.

To these and other useful ends my invention consists of parts, combinations of parts, or their equivalents and mode of operation as hereinafter described and claimed, and shown in the accompanying drawings in which,

Fig. 1 is a perspective view of a fraction of my invention.

Fig. 2 is a fractional top view of my invention.

Fig. 3 is a side view of the device as illustrated in Figure 2.

Fig. 4 is a sectional view taken on line 4—4 of Figure 2.

Fig. 5 is a sectional view taken on line 5—5 of Figure 1.

Fig. 6 is a top view of one of the chain links on which a scraper blade is pivoted.

Fig. 7 is a side elevational view of the link shown in Figure 6.

Fig. 8 is a front elevational view of a scuttle used for automatically controlling the opening in the wall of the building when the material is delivered to the exterior of the building.

Fig. 9 is a side elevational view of the scuttle as shown in Figure 8.

As thus illustrated the power and reciprocating means is designated in its entirety by reference character A. The barn gutter or barn trench is designated in its entirety by reference character B and the elevating extension trench to trench B is designated in its entirety by reference character C.

The power and reciprocating means A is preferably similar to that shown in the above referred to Patent No. 2,467,988. Other means for oscillating the mechanism may be supplied. For example: that shown in Patent No. 2,593,340.

I have shown only a fraction of gutter B in Figures 2 and 3. This may be of any needed length and the driving connections may be positioned at the end of the device as shown or otherwise.

It will be understood that my device is operated intermittently at quite infrequent intervals and generally when it is convenient to provide, say a manure spreader for the reception of the material. Attention is now called to the fact that in conventional barn gutter cleaners the material is delivered from the end of the gutter which usually protrudes through the wall of the building, so the material may be dropped by gravity on an elevator which is pro-

vided with a separate power driving unit; whereas a novel feature of my invention is that there is a single power unit.

When applicant's device extends through the wall of the building, a scuttle, which in its entirety is designated by reference character D is provided having means for automatically keeping the opening in the wall closed except for the passage of the material. Extension C to gutter B is secured to member D as shown having a curve E for an obvious purpose.

By observing Figures 1-3 it will be seen that the part of the gutter within the barn is straight for its length and that the extension C at its delivery end is in an elevated position for the purpose already recited.

Figure 4 illustrates fractionally gutter B, generally positioned within the barn, the side walls of which are designated by numerals 10 and 11 and the bottom being designated by numeral 12.

It will be noted that the trench or gutter within the barn is formed in the floor 9 of the barn and it may be of any necessary length. Power unit A may be positioned at the end of this trench as shown or in any other suitable position where it can be conveniently connected to a bar 13 by means of a pitman 14 having a suitable length and being rotatably connected at one end to endless chain 15 by means of a driving pin 16 connected to a link of chain 15 and at the other end to bar 13 as at 17 so the bar is oscillated a distance back and forth equal to the same travel of pin 16.

It will be seen that bar 13 (see Figure 3) may be any necessary length but it cannot extend into curve E. Therefore links F and G are necessary and clearly the links may be dispensed with at the outer end of the gutter extension using instead a bar 18 (see Figure 1) similar to bar 13. Blades 23 are at their inner ends pivoted on these bars or links by pins 24 as illustrated in the figures and in spaced relation. Links F and G must be provided for the part of the blade carrying means which passes into or over curve E. The blade carrying means therefore

consists of bars 13, 18 and links F and G. I provide guiding means 19, preferably an angle iron with a downwardly extending lip 19' to hold the blade carrying means in operating position.

Member A as illustrated includes a motor 21 and a transmission 22 by which chain 15 is driven.

Curve E makes necessary the use of links F and G which are hinged together by pins 24, to certain of which blades 23 are hinged at their inner ends as at 24'. Pins 24 are also secured to bars 13 and 18 wherever blades are necessary.

Figs. 6 and 7 show details of the links F to which the scraper blades 23 are pivotally connected on the upright pins 24'. The links are provided at one end with a single upstanding ear 37 and at their opposite ends with spaced upstanding ears 38 which embrace the upstanding ear 37 of the next adjacent link. These parts are pivotally connected for articulation in a vertical plane by the pins 24 shown in Fig. 1.

Each link has an abutment 47 extending laterally from face 36 thereof and against which the scraper blade 23 stops on the forward stroke of the bar 13 to hold the blade transversely across the gutter. On the rearward stroke of the bar 13, the scraper blade merely pivots on the vertical axis of pin 24 to collapse toward the vertical face 36 of link F.

I will now further describe the design and operating characteristics of my invention. The transverse shape of member C is shown in Figure 5 and it may be of any desired length other than shown in Figure 1, this member being supported partially by post 20. The sides and bottom of members C and D register with the sides and

bottom of member B, member B extending preferably through wall 25 of the building. Members C and D are preferably made from sheet steel and having flanges adapted to be secured together and to wall 25 as shown.

Member D is clearly illustrated in Figures 8 and 9, and the opening 26 of this member is considerably higher than opening 27 in wall 25. Opening 26 in member D is provided with a free closure 28 which is hinged to member D as at 29—29. Member 28 will therefore be held normally closed by gravity, but will be free to swing outwardly on hinges 29 as axes.

In view of the inclined position of member C, material being moved will be inclined to slip back by gravity. I provide means which in its entirety is designated by reference character H to prevent this, comprising posts 30—30 which are secured to the side walls of member C and held together by plates having openings for the free reception of a shaft 32, the forward posts 30 being secured together preferably by an L iron 33. A number of fingers 34 are shaped as shown and welded to member 32 in spaced relation. Thus these members 34 at their free ends will drag over the material being forced upwardly and outwardly, thus to prevent the material from sliding back. L iron 33 is preferably positioned to hold the free ends of fingers 34 a short distance from the bottom 12' of member C.

I have only shown one of members H as a matter of convenience, others may be used depending upon the length of member C.

Having thus shown and described my invention, I claim:

1. In a barn gutter comprising a side wall and a bottom having portions obliquely related in vertical profile, a barn gutter cleaner comprising a blade extending laterally across the bottom of said gutter for engagement with litter thereon, blade carrying means disposed in one corner only of said gutter, and pivot means on which said blade is carried on the blade carrying means for pivotal movement between an extended position in which it extends across the gutter and a folded position in which it is folded toward the side wall of the gutter, driving means, means connecting said driving means to said blade carrying means for driving the blade carrying means alternately in opposite directions to alternately fold and extend said blade for advancing litter in the gutter in successive increments, said connecting means being articulate in the direction in which the blade carrying means passes between said obliquely related portions, and guide means constraining said links and blades to a path of movement conforming to the profile of the gutter.

2. A device of the character described comprising a barn gutter having a side wall and a bottom having portions obliquely related in vertical profile, a reciprocating barn gutter cleaner comprising blades extending laterally across the bottom of said gutter for engagement with litter therein and blade carrying means including motion transmitting thrust links disposed in a corner of said gutter, said links having joints therebetween on which the links may articulate vertically in the course of passing between the obliquely related portions thereof, and means for reciprocating said links, said blade carrying means having a terminal end portion disposed in one of said barn gutter portions, said side wall being provided with guide means constraining said blade carrying means including said terminal end portion to a path of reciprocatory movement confined to said corner.

3. The device of claim 2 in which said guide means comprises a rib mounted on said side wall in spaced relation to said gutter bottom to receive said blade carrying means therebetween, said rib having a downwardly extending flange constraining the blade carrying means against lateral movement.

4. The device of claim 2 in which one of said obliquely related portions is upwardly inclined, in combination with check means which yieldingly rides over litter mov-

ing up said inclined portion and checks retrogressive litter movement therealong.

5. The device of claim 3 in which said links comprise base portions and upstanding terminal ears on which the respective links are jointed, the tops of said ears being within the downturned flange of said rib.

6. The device of claim 5 in which the base portions of certain of said links have upstanding hinge pins to which said blades are respectively pivotally connected, the tops of said blades being below said downturned flange to permit free articulation of said blades about said pins and beneath said flange.

7. In a barn gutter having a bottom and side wall, a reciprocating barn gutter cleaner comprising serially connected motion transmitting thrust links disposed in a corner of said gutter, said links having base portions and upstanding terminal ears on which the respective links are jointed, certain of said base portions having upstanding hinge pins and blades pivotally connected to said pins and a guide rib mounted on the side wall of the gutter and having a downturned flange embracing the tops of said link ears whereby to confine said links to a path of reciprocatory movement in the corner of said gutter, said blades being below the level of said flange for free articulation on said pins.

8. A barn gutter cleaner for installation in a barn gutter with an angular bend therein and having a smooth bottom and a side wall extending upwardly therefrom, comprising: a scraper blade adapted to rest on the bottom of the gutter and to scrape the same in one direction of movement therealong; a single reciprocable drive means for said blade adapted to extend along the upright wall of the gutter and to have one end of said blade pivoted thereto to provide for free movement of the blade from a folded non-scraping trailing position when moving along the gutter in one direction to a scraping position wherein the blade extends substantially across the bottom of the gutter when moving along the gutter in the opposite direction, a substantial portion of said reciprocable drive means being flexible to provide for an angular bend in the gutter; means adapted to be disposed adjacent the bend in the gutter for guiding said reciprocable drive means as it moves past the bend; means including a part of said drive means adapted to engage the upright side wall of the gutter for guidance thereby and to limit the pivotal movement of said blade to prevent loss of the load; and means connected to said reciprocable drive means to drive the same alternately in opposite directions to actuate said blade in the gutter whereby the blade moves material in one direction toward an end of the gutter when the blade is moved in that direction and is extended across the gutter and said blade by-passes the material in the gutter when the blade is moved in the opposite direction and is folded to a non-scraping position, said barn cleaner being characterized by being capable of removing the material in the gutter in successive increments by successive reciprocating movements of the same.

9. A barn gutter cleaner for installation in a barn gutter having an angular bend therein, said gutter having a bottom and a side wall, and comprising blade carrying means in one corner only of the gutter between its bottom and side wall, a blade, pivot means connecting said blade to the blade carrying means and on which the blade may swing between an extended position in which it extends laterally across the gutter and a folded position in which it is folded toward the side wall of the gutter, driving means, means connecting said driving means to said blade carrying means for driving the blade carrying means alternately in opposite directions to alternately fold and extend said blade for advancing litter in the gutter in successive increments, said connecting means being articulate in the direction in which the blade carrying means traverses said angular bend, and means for guiding said blade carrying means about said bend.

10. A conveyor-plow, comprising: a runner having an outer and an inner face; a scraper blade having one end vertically hinged at said inner face; stop means for limiting the rearward operating swing of the scraper blade to substantially a right angle to the runner; said runner being divided into sections pivotally connected.

11. A conveyor-plow, comprising: a runner having an outer and an inner face; a scraper blade at said inner face and having one end vertically hinged to said runner; stop means for limiting the rearward operating swing of the scraper blade to substantially a right angle to the runner; said runner being divided into sections pivotally related to each other on a horizontal axis.

12. A conveyor-plow, comprising: a runner; a scraper blade having one end vertically hinged on said runner; stop means for limiting the rearward operating swing of the scraper blade to substantially a right angle to the

runner, said runner being divided into sections pivotally connected.
